UNITED STATES PATENT OFFICE

126,233

DESIGN FOR A SERVING DISH

Albert Bartsch, Chicago, Ill.

Application April 27, 1939, Serial No. 84,596

Term of patent 14 years

To all whom it may concern:

Be it known that I, Albert Bartsch, a former citizen of Germany, who has declared his intention of becoming a citizen of the United States, residing in Chicago, in the county of Cook and State of Illinois, have invented a new, original, and ornamental Design for a Serving Dish, of which the following is a specification, reference being had to the accompanying drawing, forming a part thereof, in which:

Fig. 1 is a top plan view of the serving dish, showing my design;

Fig. 2 is an elevational view; and

Fig. 3 is a sectional view taken on the line 3—3 of Fig. 1, but with the closure cap member in elevation.

I claim:

The ornamental design for a serving dish, as shown.

ALBERT BARTSCH.
